UNITED STATES PATENT OFFICE

LIONEL HOLLAND, OF CULCUTTA, BRITISH INDIA

AEROPLANE-LANDING MEANS

Application filed August 16, 1928, Serial No. 300,078, and in British India June 12, 1928.

This invention relates to landing and/or despatching apparatus for aeroplanes or the like.

The object of the invention is to provide an apparatus which can be used to enable the landing of or despatch of aeroplanes to be effected from positions in which the aeroplane could not possibly be landed or could not take off unless some suitable apparatus was provided.

The main object is to provide means whereby aeroplanes may be landed or despatched from the centre of a city from, for example, the top of a high building, or from any other place where the necessary ground is not available for an aeroplane to take off from or to land on.

The advantages of apparatus or means for this purpose will be obvious as it would allow of landing and despatching stations to be provided in the heart of a congested city, thus enabling passengers to alight or to start on a journey without the trouble, expense and delay of having to go miles away to a suitable aerodrome.

The apparatus which is about to be described is not only suitable for use on the top of a building but could also be used on a ship or pontoon, or in any desired position where the necessary ground, or space of water, does not exist for ordinary landing and taking off purposes but where the neighborhood is not restricted by numerous high trees or buildings in its close proximity.

The invention consists of apparatus for enabling the despatching and/or landing of aeroplanes to be effected consisting of a landing mast (or tower) with a pivoted arm carried by the mast, said arm being capable of revolving around the axis of the mast and being provided with an attachment device for an aeroplane on the outer end thereof, and being so balanced and controlled that under the weight of a motionless aeroplane hanging from the end of the arm, the said arm will take up an inclined lowered limiting position, but which arm, as the aeroplane gathers speed around the mast and whilst the aeroplane is revolving around the mast attached to said arm, will take up a raised position

approaching more and more to the horizontal position with its end sweeping through a path having a larger and larger radius as the speed of the aeroplane and of the arm around the mast increases, whereby the said arm may be used to control the swinging outwards and upwards of an aeroplane as its speed increases and to control the whirling of the aeroplane around the mast until the necessary radius and flying speed is attained for the aeroplane to cast off, and, whereby, the arm being in a raised position and an aeroplane being in process of landing, the said arm, upon an aeroplane engaging its end, will swing round with the aeroplane, and the aeroplane as it loses speed will be controlled by said arm as it, in revolving around the mast, gradually sinks to a desired limiting lowered position.

It also comprises apparatus for enabling the despatching and/or landing of aeroplanes to be effected where limited space is available, consisting of a mast (or tower) with a pivoted arm having an attachment device for an aeroplane thereon and being capable of rotating around the mast and also swinging up and down in the plane of the mast, characterized by this, that the arm has means whereby it may be caused to rotate around the mast and is so balanced and controlled that, when an aeroplane is attached thereto and the said aeroplane is motionless or moving around the mast at slow speed, the arm will hang with its outer end in a lowered position but is prevented from dropping below a limiting position in which limiting position the end of the arm and the aeroplane is held or constrained to travel on a circular path having a radius sufficient to prevent the aeroplane's wing from touching the mast, and when the aeroplane is moving around the mast at a higher speed the said arm will take up a more elevated position approaching nearer and nearer to the horizontal with its end describing a circular curve of larger and larger radius as the centrifugal forces due to the speed of rotation of the aeroplane and the arm around the mast increases, for the purposes explained.

The arm is adapted to rotate about or with the mast or tower and may be pivotally at-

tached at or adjacent to the top thereof and be capable of taking up any position between a fully extended upper position in which the said arm may approach the horizontal, to a 5 limiting lower position with the arm sharply inclined to the axis of the mast or tower, the said arm when in said lower limiting position making contact with a circular track surrounding the base of the mast or tower, around which track the said lower end of the arm may slide or roll, means being provided at the outer end of the arm for the attachment and detachment of aeroplanes thereto or therefrom.

15 In said apparatus the pivoted arm may be counterbalanced easily to swing from its lower to its upper limit. It may be counterbalanced so that it will, under its own weight and balance, tend to take up a position approximating to a horizontal position or the upper limiting position.

In any case the raising and lowering of the pivoted arm may be under control; for example, be controlled by a winch or the like in some convenient manner. Alternatively, the position of the arm may be under spring control. A wheel or sector may be fixed to the pivoted arm at its pivotal point, which may be operable by cables or the like, which thus control the raising or lowering of the arm. A spring or springs may be used in combination with the cables or the like, the tension or pull in which spring or springs being such that it will, when allowed to act, cause the pivoted arm to rise to its raised and more or less horizontal position, but the tension in which can be released or relieved to enable the pivoted arm to drop to its lowered position.

In combination with the above the pivoted arm may be provided with a crank device adjacent to its pivotal point, the crank arm of which is connected to a spring and the arrangement being such that as the end of the said arm sinks the tension on the said spring is increased.

The spring arm may be connected to means whereby its initial tension may be adjusted so that the tension in the same when the arm sinks to its lower limiting position may also be adjusted to reach a desired value dependent on the anticipated weight of the aeroplane to be landed.

Further, this apparatus may be so arranged that the arm, if the aeroplane is not as heavy as is anticipated, will come to rest when an aeroplane is being landed in a position above the limiting lower position and may thereafter be lowered gently to said lower limiting position by slackening off the tension in the 60 spring.

Suitable swivelling means or revolving joints may be introduced into this cable or the like to prevent the twisting of the cable when the pivoted arm rotates about the mast.

65 Lever devices, gearing or other mechanism

may be provided by means of which the tension on the cables or the like supporting the pivoted arm may be adjusted to cause said arm to take up, or to tend to take up, a desired position.

In this apparatus the pivoted arm may be of a stiff construction in the direction of the vertical plane passing through the momentary position of the arm and the axis of its mast or tower, but may be more or less flexible 75 in a direction perpendicular to this plane.

The object of this is that when an aeroplane travelling at say a landing speed of 40 to 80 miles per hour attaches to the end of the arm the same may be whippy and to some extent 80 reduce the shock of landing.

The invention includes an aeroplane landing or launching device, comprising a mast or tower, and an arm on said part adapted to rotate about or to be rotated about the axis 85 of said arm or tower, said arm also being arranged to be capable of tilting to allow its outer end to rise and fall and being so balanced or controlled that the weight of an aeroplane when stationary or moving slowly 90 around the mast will bring the arm down to its lowered position, characterized by this that the said arm is of the lightest possible construction compatible with suitable rigidity in a vertical plane, and is capable of resisting without exceeding recognized working stresses such as the bending moments induced therein by an aeroplane hanging from the end of the arm only when the aeroplane is suspended at the reduced radius or lever-arm 100 which obtains when the arm is at a steep inclination to the axis of the mast, for example when the angle between the mast and arm is 30° or less, the said arm being capable of resisting relatively high longitudinal tensional forces applied thereto, for example the resultant force due to the weight of an aeroplane and the centrifugal forces induced owing to the rapid rotation of the aeroplane and the arm around the mast, with the object 105 that the arm may rise and revolve around the mast in a raised or elevated position to conform to the forces due to a rapidly moving aeroplane attached to the end of the arm, and may accordingly be used mainly in longitudinal tension to whirl and control the aeroplane attached thereto or to be whirled thereby 110 whilst controlling the aeroplane.

In this embodiment of the invention the said pivoted arm need have only sufficient 120 vertical rigidity to support its own weight when raised to the horizontal position, but must have ample strength to resist the longitudinal tension therein when whirling or being whirled by an aeroplane attached to or hanging outwards from the end of the arm in launching or landing.

Lightness of this arm is a most important and desirable feature owing to the fact that when an aeroplane in landing hooks onto the 125

arm it is necessary for it to overcome the inertia and to accelerate the arm, or, even if the arm is itself being rotated at the time, it may be necessary to accelerate it further or to moderate its speed of rotation. The lighter the arm is, the less is the inertia and the less the stress in the connections when alterations in speed of rotation are called for. In this particular instance the arm 10 works mainly in tension when whirling the aeroplane or being whirled thereby, and hence may be made of extremely light construction.

Under ordinary conditions the arm needs only to be strong enough to support its own 15 weight when raised to the horizontal position in which the lever arm and bending moment on the unloaded arm are a maximum. When it drops to a steep inclination the end of the arm may rest against the circular run- 20 away made for it around the base of the mast and the bending moment may be very small. Under certain conditions the arm might however be so balanced that under the weight of a very small or light aeroplane it 25 would take up a sharp inclination, such as one having an angle of less than 30° with the mast, without necessarily coming into contact with the said circular run-way, and in such conditions the arm would be given suitable 30 stiffness to sustain its own weight and the weight of the light aeroplane thereon when suspended at such smaller leverage.

In any of the apparatus according to this invention the attachment gear for attaching 35 the aeroplane to be launched is attached to the end of the pivoted arm and may be connected to cables or the like, in such manner that the said attachment may, when desired, be paid out or extended to enable the radius 40 of the curve on which the aeroplane is caused to move to be extended beyond that given by the length of the pivoted arm.

This is a feature which is important to the best operation of the method of launching. 45 When the aeroplane pivoted arm, which is in its lowered position, and the aeroplane engine is started, this causes the aeroplane and the arm to start rotating around the axis of the mast at gradually increasing speeds. If 50 desired the mechanism which itself rotates the arm may be started to assist in accelerating both the arm and the aeroplane hanging from it, to revolve faster and faster around the mast. After a certain speed has been attained and exceeded the end of the arm leaves the track around the base of the mast against which it had up to that time rested and swings outwards. As the arm with the aeroplane swings outwards the centrifugal forces 55 acting thereon rise rapidly. It is important to keep these centrifugal forces as low as possible for any particular speed of movement of the aeroplane around the mast. This can be done by increasing the radius on which 60 the aeroplane is moving when at any partic-

ular speed. The radius can be increased by paying out the attachment to the aeroplane so that instead of being held tight to the end of the rotating inclined arm it is allowed to run out gradually. The paying out of the 70 attachment must be controlled either manually or automatically so that it does not start until the aeroplane has sufficient ground clearance, and does not extend to such a point that the aeroplane is completely out of control or can suffer an accident; that is to say, until the aeroplane has closely approached 75 the speed at which it will fly unaided the attachment should not be let out so far that the aeroplane, if it suddenly stalled or upset in a gust of wind, could drop to the ground, but on the contrary it should be supported clear of the ground by the attachment to the end of the arm. This however will allow 80 of very substantial extension of or letting 85 out of the attachment when the speed is high and the arm has risen. It will be understood moreover that the arm, as well as swinging up with the aeroplane may by its counter-weight, or under its spring or other control, 90 be caused to swing up ahead, or slightly ahead, of the aeroplane as the same is being let out. The arm instead of acting as a brake may thus help to slightly lift the aeroplane. 95 It will further be understood that when flying speed is attained the aeroplane whilst still attached to the arm may even rise above the arm when the flexible cables to which it is attached are let out. During all these operations the arm will mainly be under longitudinal 100 tensional stresses.

In this apparatus the pivoted arm, instead of being inert and merely capable of rotation under the impulse given to it or the forces applied to it by the aeroplane, may be capable 105 of rotation around or about the mast or tower, and means may be provided whereby the said arm may positively be made to rotate.

The pivoted arm may be adapted to be rotated by gearing or by a cable, rope or the like passing around the rotatable head carrying the arm, said cable or the like passing around jockey pulleys or the like and then to the drum of a winch, or other driving or rotating mechanism preferably driven by a suitable engine or motor, said mechanism being capable of rotating the pivoted arm at a desired speed.

A disengaging or free-wheeling device may be introduced so that the pivoted arm 120 may rotate freely when an aeroplane is landing irrespective of the driving mechanism being in gear or not.

The rotating pivoted arm may have a vane or the like fixed to the pivoted end, which 125 vane is in line with, or at an angle to, the arm, and is adapted to cause the arm to take up a desired position relatively to the direction the wind is blowing.

The pivoted arm may have a wheel at its 130

outer end mounted on suitable bearings, which wheel, when the arm descends to its limiting lowest position, engages and is adapted to run round the track provided for the purpose around the lower end of the mast or tower.

The tower or mast will be of relatively small diameter below the circular track around the lower part thereof, so that the wings of the aeroplane may enter below the track; and the tower may have, above the said circular track around its base, a working platform carrying thereon the arm raising and lowering gear, the arm rotating gear and/or the aeroplane attachment paying out gear, and the winches or engines to work the same.

The apparatus may have as the attachment device to which the aeroplane is connected a ring, hoop or the like, for example of wire rope held spread out by spring means, with means whereby the plane of the ring or the like may be turned to be parallel to or to lie in the vertical plane passing through the pivoted arm.

According to a further part of this invention the attaching device on the aeroplane may have a horn or the like adapted to enter the ring, hoop or the like on the pivoted arm of the apparatus and to cause the attaching device on the aeroplane to engage said ring, hoop or the like.

The horn on the attaching or detaching device on the aeroplane may lead to a hook having a curved over or internally concave top part in which the ring or the like of the attaching device on the pivoted arm takes when the aeroplane is travelling at speed and hooks on to the attaching device. This hook may have a safety catch, pawl or spring device which will prevent the attachment parts from coming adrift when once the two have made connection.

The said attaching and detaching device in the aeroplane may be capable of being, under the control of the aeroplane's pilot, rotatable about a vertical axis so that the horn points backwards when the aeroplane is about to detach from the pivoted arm on starting a flight, the arrangement being such that when so rotated so that the horn points backwards the safety catch or like retaining device shall or may be made inoperative to release the aeroplane on its gaining flying speed.

To the attaching or hooking on device on the aeroplane a spring may be fitted enabling the shock on sudden attachment to the pivoted arm to be cushioned, the said spring device preferably showing on a scale in the cock-pit of the aeroplane the pull developed in the attachment.

The attachments may be so arranged that the engaging hook on the aeroplane is connected by rods or cables to the landing wheels

or axles of the aeroplane so that any sudden tension on the hook is transmitted to the aeroplane structure directly or partially through the springs of the aeroplane landing gear.

The said device may be so arranged that the aeroplane shall be capable of hanging from the hook thereof and the connections be made to the body of the plane in such manner and of such robustness that they are capable of withstanding a tension equivalent to at least three to four times the weight of the aeroplane.

The invention will now be described with reference to the accompanying drawings which show, merely by way of illustration and largely in a diagrammatic manner, certain forms the different parts of the apparatus may take. In these drawings:

Fig. 1 is a diagram of the apparatus.

Fig. 2 is an elevation of a tower and pivoted arm giving greater details and certain indications of constructional details.

Fig. 3 shows diagrammatically gear for causing the pivoted arm to lift or drop positively.

Fig. 4 is a diagram illustrating the paying out gear for allowing the attachment device for the aeroplane to extend.

Fig. 5 is a diagram showing the attachment of multiple part blocks and tackle between the springs of the paying out device and the aeroplane attachment ring. It also shows how the tension on the cable for supporting the arm increases as the arm sinks lower and lower.

Figs. 6 and 7 show in some detail how the last two devices may be combined.

Figs. 8 and 9 show the attaching device on the end of the pivoted arm and the cable attachments.

Fig. 10 indicates means whereby the pivoted arm may positively be made to rotate.

Figs. 11 and 12 show the attaching and detaching device on an aeroplane.

Fig. 13 shows a spring controlled connection in the device carried by the aeroplane and a scale to show the pull, and

Fig. 14 is a diagram explaining certain considerations which reduce the shock upon the apparatus on the landing of an aeroplane.

The invention consists of a device for launching aeroplanes into the air and for landing aeroplanes from the air.

It comprises essentially a mast (which is very strongly fixed either to the ground, to any building, to a ship or other structure stationary or moving of sufficient strength for the purpose) from the top of which projects a freely revolving and rising and falling arm 2. At the end of the arm further away from the mast is a ring, hoop or loop, or other attaching and releasing arrangement 3 the counter-part of which ring or other ar-

5 arrangement is mounted upon or built into the aeroplane or aeroplanes which it is intended shall be launched from or landed upon the arm and mast. The counterpart of the ring 5 may on the aeroplane consist of any suitable shape of hook or grappling hook 4 having a projection or horn 5 which the pilot of the aeroplane by so steering the aeroplane is capable of causing to attach itself to the said 10 ring or other arrangement 3; or, vice versa, the hook may be at the end of the arm and the ring on the aeroplane. This attaching arrangement is also arranged so that when ascending into the air the pilot of the aeroplane can by the movement of certain handles or other arrangement 6 cause the ring and hook to release themselves and separate.

15 Near the base of the mast is mounted a circular track 7 so arranged and of such size 20 and position that a wheel 8 mounted upon and revolving upon the arm 2 may run upon said track and thus prevent the arm 2 fouling or rubbing against the mast and also enabling the aeroplane when it is moving slowly 25 to revolve round the mast near its base suspended from the top of the mast by means of the arm 2, the arm then resting against the track 7 being supported on the aforesaid wheel 8.

30 The arm is pivoted at 10 and may be counterbalanced, for example by a weight 11, in such a manner that (when no aeroplane is to be launched) it comes to rest projecting out more or less horizontally as at 2^a—that 35 is to say in a position suitable for enabling an arriving aeroplane to attach itself to the outer extremity of the arm.

40 The foregoing parts of this invention are described more fully hereinafter, but are sufficient to make the principle of this invention clear. The method of operation is as follows:—

45 To commence with the launching of an aeroplane into the air; the aeroplane is suspended from the hook 3 and the arm 2 is resting against the track 7 supported from the track on wheel 8; the propeller of the aeroplane is revolved in the ordinary way and causes the aeroplane to move forward, the wheel 8 running on the track 7, and the aeroplane following a circular path around the mast 1 still suspended from the freely revolving arm 2; as the speed increases the aeroplane 50 and arm 2 begin to leave the track still revolving round the mast because the centrifugal force of the aeroplane and arm going round cause them to swing out from the mast and to revolve round the mast at a greater radius, which radius will go on increasing 55 as the speed increases; but the centrifugal force is not the only force tending to cause the aeroplane and arm to swing outwards and upwards and to revolve at a greater radius, the pilot of the aeroplane soon has 60 some air pressure on the aeroplane wings to

make use of and he so uses this and steers the aeroplane that it also tends to raise the aeroplane and arm upwards and outwards and to revolve at a greater radius as the speed increases; there is also a third force which 70 may or may not be used without effecting the principle of the invention, and that is the arm 2 by means of its counterbalance 11 or owing to a spring tension applied thereto is tending to assist in lifting the aeroplane and to take up the position 2^a. It will thus be seen that as the speed (on its more or less circular path) of the aeroplane increases it will 75 occupy a more and more outward and upward position until by means of its speed through the air it is supported upon its own planes; when this state of affairs is reached it is merely necessary for the aeroplane pilot to move the necessary handle 6 or levers, or operate such other arrangement as may be in use, to cause the ring or loop 3 and hook 4 or other attaching arrangement which was holding the aeroplane to the arm to disengage themselves and then the aeroplane is 80 completely separated from the arm and mast 85 and proceeds on its journey.

85 The landing of the aeroplane is a reversal of the sequence of the events described in the launching and may be explained as follows. The arm of the mast by means of its counterbalance 11 or owing to the tension in lifting ropes to be described later when no aeroplane is attached to it, is arranged to take up a more or less horizontal position as at 2^a; the ring 3 or other attaching arrangement is also 90 ready to receive and be engaged by its counterpart 4 which is attached to or forms part of the aeroplane; the aeroplane which is to be landed approaches the end of the arm in a direction more or less at right angles to the arm and is steered in such a way as will cause the horn 5 and hook 4 on the aeroplane to catch on to the ring 3 on the arm 2, or as will 95 cause the attaching arrangements of the aeroplane and the arm of whatever type they may be to engage in one another and lock securely together in such a way that they cannot be disengaged or unlocked unless the pilot of the aeroplane by the moving of a certain handle, levers or other arrangements causes the aforesaid ring and hook or other attaching arrangements to disengage and separate; but at 100 the time of landing this would not be done so that the aeroplane becomes attached or locked to the end of the arm at 2^a and draws the arm with it; the aeroplane being hooked on cannot proceed any further in a straight direction because it is now attached to the end of the freely revolving arm and the momentum 105 which the aeroplane possesses causes it to draw the arm with it and to take up a circular path and revolve round the mast. The arm may or may not be constructed so that it is more or less flexible in the direction which is 110 more or less the direction of the path of the 115 aeroplane.

areoplane at the time of its becoming attached thereto so as to minimize as much as possible the shock to the aeroplane and to the arm and mast at the time that the aeroplane becomes attached to the end of the arm; further the arm itself, and more particularly its outer-most portions, is made as light as possible also so as to minimize the aforesaid shock. Now when landing an aeroplane the pilot slows up or stops the propeller, either before, at the time of, or soon after the aeroplane has become attached to the arm; so that the weight of the aeroplane going round the mast at a decreasing speed gradually causes the aeroplane to revolve in a position lower and nearer to the mast, because the centrifugal force holding the aeroplane extended outwards is gradually becoming less and less and because the lift of the aeroplane on its own planes is also becoming less and less as the speed of translation drops until the wheel 8 on the arms rests against and revolves upon the track 7 at the base of the mast, and, finally, the propeller being stopped altogether, the aeroplane will come to rest hanging from the arm in the latter's lower-most position. It is more or less incumbent upon the pilot of the aeroplane to steer the aeroplane in a truly spiral and regular path around the mast in spite of the wind tending to cause the aeroplane to rise on one side when meeting the wind and fall on the other side when traveling with the wind. This the pilot does by moving his planes or vanes in the usual manner known to pilots.

Referring now to Fig. 1 let us assume that the length of the mast or tower 1 from the level of the track 7 to the pivotal point of the arm 2 is 150'. Further let us assume that the radius of the track 7 is about 40'. Below the track 7 the diameter of the mast or tower must be reduced at 12 to be the least compatible with strength. The height H of this reduced portion must be ample to receive the largest aeroplane to be handled between the supports of the track 7 and the ground or surface below. Such clearances as are reasonable to allow of tilting of the wings must be provided. With a track 40' in radius it is probable that aeroplane having wing spans up to 70 feet or thereabouts could be accommodated.

With the dimensions indicated above an aeroplane would have to attain a speed of 12 or 13 miles per hour around the track 7 before it had any tendency to leave the track and swing outwards, owing to the centrifugal force thereon. The arm 2 would swing outwards to the position 2^b making an angle of 30° with the vertical when a speed of 25 or 26 miles per hour is attained. These speeds neglect the influence due to the wind pressure on the wings of the aeroplane which at such a speed as 25 miles per hour would be beginning to have a very distinct influence,

These speeds also neglect the counterbalance or pull on the arm which may cause it to rise further still.

As the speed of the aeroplane rises still further the arm 2 rises and the radius on which the aeroplane is moving also increases. When the arm is at 45° with the vertical, as indicated at 2^c, the speed will be about 40 miles per hour neglecting the lift of the planes. Such a speed is one approaching that at which the aeroplane will have gathered speed enough to fly. The end of the arm 2 is then in position 2^c moving on a radius of about 110'.

It will be obvious that shortly after the arm reaches an angle of 45° the plane will have acquired flying speed. This speed depends on the type of aeroplane and the load carried thereby.

When the arm reaches a position making an angle of 60° with the vertical, as indicated at 2^d, the speed of rotation of the aeroplane will be about 60 miles per hour if it is still attached to the end of the arm. Most aeroplanes should have sufficient lift to fly before this speed is reached. The plane if secured to the end of the arm will be steeply inclined to the horizontal as it is being forced round in a circle the diameter of which is about 270'. The pull on the attachment and along the centre of the arm will be, neglecting the effect of the lift on the wings, about twice that of the weight of the aeroplane.

To reduce the heavy tilt on the aeroplane and also the rate of revolution of the arm—which under the conditions suggested above would vary from about 4½ revolutions per minute when the arm is at 30° to 6 revolutions per minute when the arm is at 60°, the attachment 3 might be paid out. Let us assume the attachment 3 is paid out so that it starts lengthening when the arm has reached an angle of 30° and has lengthened the arm by 75' when the arm reaches an angle of 60°.

The radius at which the aeroplane is moving when the arm is at 60° and the attachment has paid out to this extent is about 200' and the aeroplane would have to exceed a speed of 70 miles per hour on this radius to hold the arm out at this angle.

By paying out the attachment the radius on which the aeroplane is moving is at once increased and accordingly the centrifugal force exerted by the aeroplane on the attachment at the speed it is travelling at the moment is reduced. The result of paying out the attachment suddenly with the arm revolving at any particular angle would be that the length of cable connecting the end of the arm to the aeroplane would at first drop below the angle reached by the arm, the actual revolutions per minute of the arm would momentarily drop and the aeroplane would sink slightly till its speed further increased.

5 By paying out the attachment gradually the aeroplane would attain to a flying speed before the arm 2 had risen as high as it otherwise would have to rise and would also attain this speed with less centrifugal force on the connections and being on a larger radius it would not be tilted to the same extent when about to be cast off.

10 As will hereinafter be explained the arm 2 may be caused to rise by positive means such as by the action of a winch so that the arm might be used to lift the aeroplane higher than it would be lifted by its centrifugal force and hence the aeroplane hanging below the end of the arm in a paid off position be still well clear of the ground.

15 For example, as the aeroplane gathers speed and the attachment pays out the loop 3 when the arm is at 2^a might be at 3^c , when the arm is at 2^a at 3^d , and when the arm is at 2^a be at 3^a . The aeroplane would then swing out on the dotted curve $3, 3^c, 3^d, 3^a$ and be in a very much better position as far as centrifugal force thereon and tilting thereof than otherwise.

20 Fig. 3 indicates a means whereby the arm 2 may be caused to rise or fall as desired. For example to enable a second aeroplane and any other aeroplane to be launched after one has been launched and has caused the arm to remain in the more or less horizontal position 2^a . Now the counterbalancing of the arm may be carried out as follows:—

25 The inner end of the arm is pivoted upon a centre 10, about which centre the arm rises and falls as hereinbefore described. Upon the same centre 10 and built into and forming part of the arm may be a wheel or sector of a wheel 14. Around this wheel or sector passes a strong flexible rope or cable 15 the end of which is connected to the periphery of the wheel at 16. The rope or cable then passes down the middle or near the middle of the mast 1 being brought to the required position either by making the wheel of the requisite diameter or by the insertion of a jockey pulley 17, it then passes to and is fastened to a freely revolvable joint 18. This joint enables the upper part of the rope or cable 15 which has just been described to revolve freely with the arm 2 as this revolves round and round the mast 1 without twisting the lower portion of the rope or cable 19 (which is just about to be described) with it. The lower portion of the rope or cable 19 then passes from the lower end of the revolvable joint to a spring or springs 20 and the strength of this spring or springs is so adjusted that the tension therein is normally sufficient to raise the arm until it occupies the more or less horizontal position. The lower extremity of this spring or springs is fastened to a spring tension adjusting lever 21 which may be provided with a catch which may be operated to cause the said lever to remain in either of two positions. This lever may be so arranged

30 that when it is in one position (the lower one), indicated at 21, the arm 2 without any aeroplane on it would occupy the more or less horizontal position 2^a and with an aeroplane on it would then occupy the lowermost position, the weight of the aeroplane having caused the counterbalancing spring or springs to be stretched sufficiently to allow the arm to descend to this position resting against the circular track 7 around the mast. It will thus be seen that when the spring tension adjusting lever is in its lower position 21^a , and an aeroplane has just been launched the arm is in its upper more or less horizontal position 2^a . Now when it is desired to despatch from the base of the mast a second or subsequent aeroplanes, preparatory to launching the arm is required to be lowered. Therefore the spring tension adjusting lever is so arranged that it may be moved to its upper position 21^b to allow of sufficient slackness to be given to the spring, rope or cable 20, 19, 15 that the weight of the arm will cause it to descend to its lower position 2; and then the ring or other attaching device 3 at the end of the arm may be attached to its counterpart on the next aeroplane which it is desired to launch; then when the next aeroplane has been attached the spring tension adjusting lever is removed to its lower position 21^a and thus imparts an outward and upward pull to the arm so that it is trying to raise the aeroplane and occupy the more or less horizontal position 2^a so that the next aeroplane can then be launched as hereinbefore described. In a similar manner any number of aeroplanes may be launched.

35 If it is desired to land a second aeroplane or subsequent aeroplanes the operation is effected as follows:—The first one which has been landed is hanging on the end 3 of the arm. The spring tension adjusting lever is then moved to its upper position 21^b which reduces the outward and upward pull in the arm. Some support under the aeroplane or under the aeroplane's wheels is then moved or pushed into position so that the aeroplane is raised sufficiently to remove its weight from the ring of hook or other attaching device upon which it is hanging at the end of the arm to enable the said ring or hook or other attaching device to be detached and completely separated, and which thus enables the aeroplane to be wheeled or moved away from the mast altogether. But as an alternative provision may be made for lowering the aeroplane from the end of the arm by the operation of levers or by paying off the cable holding the attachment 3 so that it rests on its own wheels or otherwise upon the ground or other support and may similarly be moved or wheeled away from the mast altogether. The spring tension adjusting lever is then gradually moved to its lower position 21^a , and in moving it the arm is thereby raised to

the raised position 2^a. If so desired the spring tension adjusting lever or its equivalent may be arranged with gearing so that by rocking it to and fro or by providing it with suitable gear ratios it will be within the strength of one man to raise the arm to raised position. The auxiliary wheel or sector may be replaced by two or more wheels or sectors in which case two or more ropes or flexible cables would be provided from the anchoring positions on the wheels or sectors to the revolving joint. Similarly two or more ropes or flexible cables may be provided between the revolving joint and the spring adjusting lever or equivalent. The object to be obtained by having more than one rope or flexible cable may be either that of enabling the revolving joint to be constructed with an opening right through its centre to allow of the passage through it of other ropes or cables hereinafter described, or that of getting greater flexibility, or that of getting a greater margin of safety.

A further auxiliary device, which may or may not be employed to work in conjunction with this invention, is illustrated diagrammatically in Fig. 4 and has either or both of the following objects in view—firstly that of minimizing or reducing the shock to the arm and to the aeroplane at the time that the aeroplane to be landed becomes attached to the end of the arm, and secondly that of increasing the radius at which the aeroplane revolves around the mast at either or both of the following times; firstly, immediately following that at which it has just become attached to the arm, or, secondly previously to the moment at which it becomes detached from the arm; for at either or both of these times the impact on the arm and on the aeroplane and the discomfort felt by the occupants of the aeroplane owing to the effects of the centrifugal force due to the circular motion of the aeroplane around the mast are likely to be at a maximum and to vary inversely as the radius of the curve on which the plane is forced to move. This device is such that it enables the ring or hook 3 or other attaching device at the end of the arm 2, when a pull is exerted upon it by an aeroplane attached thereto, which pull is greater in force than the dead weight of the aeroplane, to be drawn out further and extended outwards away from the normal position at the end of the arm which it occupies when the aeroplane is either hanging stationary from the arm or is only revolving slowly around the mast. This capability of the ring or hook or other attaching device of being drawn out in the above circumstances is attained by having the aforesaid ring or connecting device fastened to the end of a sliding rod or tube or to a flexible cable or rope, or a combination of these things, the other end of which is attached to a spring of such

strength and so arranged that it can only be stretched out or lengthened when a pull is exerted exceeding the dead weight of the aeroplane. The other or fixed end of the spring is attached to a strong anchorage either within the arm itself or within the mast, and in cases where the fixed end is attached to an anchorage within the mast then a revolving joint is interposed at any convenient point between the place where the sliding rod or tube or flexible cable or rope has its direction of force changed at the top of the mast and the position of the anchorage.

In Fig. 4 the attachment device 3 is connected to the cable 22 preferably in such a manner that the base of the said attachment may be pulled up tight against a stop or seating 23 in the end of the arm 2. The cable passes down the arm 2 and around a pulley 24. It then passes down the mast or tower being provided with a swivel or equivalent 25. Very powerful springs 26 may be attached to the cable and the end of the cable 27 passes around the drum of a winch 28. If springs 26 are introduced into the cable the strength of these springs should be such that they will be capable of resisting the maximum pull due to the heaviest aeroplane to be handled plus the centrifugal force. It will readily be understood that the centrifugal force when the arm rises to above an angle of 60° to the vertical may approach to or be double the weight of the aeroplane. The spring or springs 26 must be capable of resisting this with a suitable margin of safety.

Further, these springs 26 should be capable of a considerable amount of extension. As indicated in Fig. 4 the spring could scarcely extend or contract to an amount exceeding say 35% of the length of the arm 2, but it may be possible to provide some multiplying arrangement whereby the attachment 3 may be paid out to a greater extent than this. Such a multiplying arrangement is shown in Figs. 5, 6 and 7.

If a spring is introduced capable of extending to a length equivalent to 90% of the height of the mast 1 when the maximum stress is thrown on the connections in landing an extra heavy aeroplane at high speed it is preferable that such a spring should be placed under an initial tension before the aeroplane is hooked on, which initial tension should be about equivalent to the weight of the plane so that the aeroplane by the time the arm 2 comes to rest in its lowered position will be held up to the end of the arm by the initial tension in the connections. The cable 27 may therefore be connected to a winch 28, which winch might conveniently have certain indications such as 1 ton, 2 tons, 3 tons—to indicate the initial tension in the spring with the drum in the said positions.

A single device suitable for giving a spring extension of say 35% of the length of the arm when landing a very large aeroplane would give but little extension—perhaps only a 5% extension when landing a very light plane. A light plane would accordingly be subjected to higher relative impact in stress than a heavy one under the lesser extension and it may be found advisable to duplicate or 10 triplicate the devices shown in Fig. 4 and to design separate springs to handle respectively light, medium and heavy planes.

It is not absolutely essential to have a spring or springs 26 fitted as it would be quite possible by using a cable which could be paid out, say under the brake or friction control of a winch drum, or under control of hydraulic or like braking gear, to reduce the shock in landing an aeroplane and reduce the stresses and the tilting of the machine in assisting planes to take off. In such cases the plane when hooked on when landing would pull out the cable under heavy brake resistance and the said cable would be wound in again so as to 25 pull the aeroplane hard up against stop 23 before the arm came to rest in its lower position. When an aeroplane was to be assisted in getting off the cable would be let out gradually as found requisite.

With a paying off gear it will be evident that facility in attaching or detaching of an aeroplane to or from the arm when in lowered position would be greatly increased, as all that would be needed would be to use the winch 28 to pay off the rope 22 to lower the aeroplanes gently to earth, or conversely to slack off the attachment ring 3 until it could be hooked on to the aeroplane on the ground or surface 13 below and then to lift the aeroplane up against the stops 23 on the arm by tightening the rope 22 as requisite.

The rope 22 may have a device 34 clamped thereto which may take up against a buffer stop 25 when the rope has pulled out to the 25 limits which it is desired should not be exceeded.

Referring now to Fig. 5 the one end of the two part cable 22^a which passes to and is attached to the aeroplane attaching ring 3 passes round the jockey pulley 24^a and to the swivel or like joint 25^a and thence to the anchorage 65. The other part 22^c of this cable after passing over a jockey pulley and through the revolving joint 25^a passes to the multiple blocks 66, 67. This system of blocks is shown in the figure as having eight parts. The attachment ring 3 therefore would have an extension of four times the extension of the springs 26^a.

The lower 66 of the set of blocks is attached to the springs 26^a and has guide members adapted to slide up and down the slide bars 68, 68, as far as the stops 69. The springs 27^a are connected to the cross bar 71 and this is connected by the cable 27^a to a

winch drum 28^a. Any desired tension within certain understood limits may be placed on the springs by working or paying out the winch 28^a.

The upper set of blocks 67 is attached to a member 72 which has a rotatable joint 73 therein. The upper end of 72 is connected at 16^a to a crank arm 14^a fixed to the pivot 10 of the arm 2.

It will be realized that assuming the difference in level of the end 16^a of the crank 14^a between positions 2 and 2^a of the arm is say 4' 0" and the spring when extended by 4' 0" requires an extra tension of 1 ton on the ring 3 to so extend it, then as the arm drops from 2^a to 2 block 67 rises 4' 0" and the block 6 rises a little over 3' 0" and the initial pull on the ring 3 is increased automatically to an amount of about three quarters of a ton. By these means the initial tension on the ring 3 with the arm in raised position may be increased, to say $\frac{3}{4}$ of a ton, on the arm falling, with the result that it may be so arranged that it will certainly raise the pull on the attachment to be above that due to the pull caused by the weight of the aeroplane itself when the arm is in said lowered position.

Referring further to Fig. 5 it will be seen that any desired tension may be placed on the ring 3 with the arm raised. This adjustment will be effected by the winch 28^a. Upon an aeroplane attaching to the end of the arm a sudden pull is applied to the attachment 3. Assuming for the moment that this pull reaches a maximum value of say three tons on the ring 3 and that a pull of three tons is equivalent to a lengthening of the springs 26^a by a distance of twelve feet; then owing to the multiplication given by the blocks and tackle arrangement 66-67 the ring moves outward by approximately 48 feet thus reducing the shock of the connecting operation.

As the speed of the aeroplane attached to the arm around the mast falls off, this pull drops drawing the ring 3 in towards its stop 23 on the end of the arm. As however the arm falls the other factor comes into operation increasing the pull on the ring 3 as the arm falls lower and lower. The numerical values of the tensions will of course be varied to suit the size and weight of the planes to be handled and will depend on the details of construction.

Figs. 8 and 9 illustrate one possible embodiment of the attachment for the aeroplane to hook onto and shows also the end of the paying out gear.

In these figures 3 is a ring or hoop or loop or wire kept open by light spring arms of adequate strength to take the pull. This ring or loop 3 has a hook or tang 29 having a T end 30. The said T head drops due to gravity into a recess 31 in the yoke 32. The

wire ropes (of which two are shown) 22 are attached to the yoke and the back 33 of the yoke may be shaped to be capable of taking a comfortable seating on the stop 23 on the end of the arm 2. The ropes 22 pass around 5 pulleys 36, 36 and are held in position thereon by guide rollers 37, 37. An equalizing device 38 to equalize the pull on the ropes may be fitted.

10 The direction of the T head 30 and its shape forces the ring loop to take up a position with its plane perpendicular to the direction from which the aeroplane is expected to come—which direction is perpendicular to the arm 2.

15 In Fig. 10 a means for causing the arm 2 to rotate around the mast is shown.

In this the endless ropes 40 which are passed around the drum of a suitable winch, 20 rotating mechanism or the like 43 pass up to the top of the mast and around a pair of jockey pulleys 41 and thence around the large rope pulley 42.

25 This rope pulley is fixed to the revolving head 44 which carries the pivot 10 on which the arm rises and falls. By working the winch 43 the arm 2 may be made to revolve about the mast 1 whether an aeroplane is attached or not.

30 A free wheeling or disengaging arrangement (not shown) must be provided enabling the revolving head 44 to rotate freely without check from the winch or driving mechanism 43 when an aeroplane suddenly hooks 35 onto the arm.

35 The causing of the arm to rotate about the mast by means of gearing or other mechanism may be of great assistance, since the extra assistance so given to an aeroplane as it is trying to take off may be of very great 40 importance to it as assisting to overcome the frictional resistance in moving on a curve. The positive driving of the arm shortly before the aeroplane has gathered 45 flying speed and the paying out of the attachments so as to both assist the aeroplane to gather speed on its curved path and to increase the radius of the path on which the plane is flying and to thus reduce its tilt at the moment of casting off, may indeed be 50 found almost essential.

Further, with mechanism to positively cause the arm to rotate it may or may not be 55 found possible for an aeroplane to hook onto an arm when landing which arm is already rotating. If this can be done the shock to the arm and the apparatus may be considerably reduced and the stresses and strains in the parts be thus reduced both in the mast and 60 arm and also in the aeroplane itself. In order to hook onto a rotating arm it would probably be necessary for the pilot to approach the mast on a curve or spiral.

65 In Figs. 11 and 12 device is shown which could be fitted to an aeroplane to make it pos-

sible for it to be launched or received with apparatus as hereinbefore described. Assuming that a ring loop 3 is attached to or carried by the end of the arm 2 then a hook 4 having a 70 projecting horn 5 is mounted on the aeroplane.

In Fig. 11 the apparatus is shown in its normal position—that is the position in which it would be when the aeroplane is about to attach to the ring 3 or when it is so attached. 75

The point 45 of the horn is above and in advance of the pilot so that he can see clearly how to steer the plane to cause the point of the horn to enter the ring or hoop 3. The horn runs through the said ring loop 3 and causes the hook part 4 to engage the ring. A spring pawl 46 or catch prevents the parts from disengaging. When hooked on, the ring takes onto the concave bend 47 at the top of the hook and the strain is taken with the ring loop 3 in the position shown in dotted lines. The hook is strongly stayed to the aeroplane body as the stress thereon may exceed that due to the weight of the plane itself by two or more times depending upon the length of the 80 arm 2 and the radius of the curve in which the aeroplane is caused to travel, and also upon the impact or relative suddenness with which the plane hooks on. A shaft 48 operated by the handle 49 in the cockpit of the aeroplane 85 permits the hook to be rotated from its normal position with the point 45 of the horn pointing forward to the reverse position when it is desired to cause the aeroplane to detach itself 90 from the ring 3.

95 In Fig. 12 the hook is shown when in a position to detach from the ring. The horn 5 points backwards owing to the turning of the shaft 48 and handle 49. The disengaging member 50 which is fixed to the aeroplane 100 structure, has, as the shaft 48 and hook 4 turns, engaged and pressed down the pawl 46 so that it no longer closes the throat 51 of the hook. When the pilot judges that he has sufficient flying speed he guides his aeroplane so 105 that flying on the proper curve it also lifts so that the part 47 of the hook instead of engaging the ring or loop 3 lifts clear thereof and the plane disengages from the ring and flies clear. It will be observed that this cannot be done until a reasonable flying speed has 110 been attained otherwise the part 47 of the hook cannot be caused to lift clear.

115 The ring on the arm 2 should be so arranged that it will tend always to take up a position under its own weight which will make it hang in its yoke with its plane properly placed to receive the hook of an aeroplane to be hooked on. The formation of the T shaped tang 30 of the hook might be such that it would, provided the pull on the ring 3 is not too much, 120 allow the ring to rise slightly and to twist through 180° C. The reduction of stress on the hook and ring might be the criterion by which the pilot would judge whether he could 125 130

cast off. Obviously he must not cast off until he has flying speed, when he judges he has this speed he by guiding his aeroplane upwards and inwards will be able to judge by testing whether he can turn the handle 49 whether the stress on the attachment is still excessive or not. When he can turn the handle he has momentarily attained the desired speed and is flying on the proper curve. Shortly afterwards he may steer the plane more steeply upwards and inwards and cast off.

The attachment shown in Figs. 11 and 12 might be modified so that when landing the horn 5 pointed forward all the time and when an aeroplane was to be launched it pointed back all the time. In the latter case the release of the spring catch 50 would preferably be operable by means independent of the handle 49 so that the catch was only released after the pilot thought he had attained flying speed.

Fig. 13 shows a modification of the attaching arrangements carried by the aeroplane wherein a spring 74 placed in the barrel 74^a reduces the shock of the sudden pull on hooking onto the ring loop 3. The scale 75 may show the pilot in the cockpit the strain in the rod 48, when, in the operation of launching, the said scale indicates little or no stress, the pilot will know that he is largely supported by the air pressure on his wings and that he may prepare for casting off.

As an alternative, (not illustrated) the hook 4 may transfer the pull through suitable rods or cables to the axle of the landing wheels of the aeroplane and by these means the springs of such landing gear be utilized to reduce the shock to the aeroplane itself.

Fig. 14 illustrates diagrammatically the reception or landing of an aeroplane when a paying out attachment gear is used.

Suppose the aeroplane 9 is flying in the direction of arrow 52 and hooks onto the arm 2^a at 53. This arm previously will have been raised to nearly the horizontal position so as to give as much clearance above ground as possible.

On hooking on at 53 the attachment starts pulling out either under spring frictional or brake control. By the time the end of the arm 2^a has got to point 54^a the aeroplane is at point 54. When the end of the arm is at 55^a the aeroplane is at 55. By the time the arm is at 56^a the aeroplane is at 56.

We will assume that the spring resistance or the frictional or other resistance will only allow the attachments to pay out under the weight, speed and centrifugal forces developed, by a distance D. The radius of the curve to which the aeroplane is forced to fly within a time limit of say two seconds after attaching on is $D+R$. But it has had this time within which to change its course. The curve traced by the plane is 53, 54, 55, 56, 57 and this is a transition curve—that is one whose radius de-

creases accordingly to some law from infinity, if the aeroplane is originally moving straight on the tangent—to a radius which may fall to the radius R but will finally become $D+R$.

It will be noted that the various positions 54^a, 55^a, 56^a, of the end of the arm lie behind the positions 54, 55, 56 of the aeroplane at the same instant owing to the inertia of the arm. There will therefore be a distinct bend where the attachments join the arm. The angle 59 between the line of action of the attachments and the direction of the arm tends to increase as the arm gathers speed.

Shock on the attachments may be reduced by making the arm rather whippy horizontally. This may be effected by making knuckle joints in the arm controlled by springs so that if necessary the arm under lateral stress will deflect or bow considerably. In Fig. 14 the bending of the arm is clearly indicated and it will be clear that a certain amount of give is desirable.

Upon hooking onto the arm a considerable stress and strain is thrown on the apparatus and on the aeroplane. The transition curve 53, 54, 55, 56 joining the tangent 57 which is desired to force the aeroplane to follow much reduces shock and stress.

The pilot by approaching on a curve as indicated by arrow 58 can also help to reduce the shock. Also it is of course necessary for the pilot to bank rapidly at the moment of, or preferably just before, attaching.

Returning now to Fig. 2 which shows, still somewhat diagrammatically, a constructional form.

The mast 1 has a revolving head 44 carrying the pivoted arm 2. Around the base of the mast the circular track 7 is built. If desired the track may be supported through the medium of springs 60 on a braced structure 61.

The wheel 8 on the arm runs on this track. This wheel, or any equivalent skidding or rolling device, might be mounted on springs or be fitted with pneumatic tyres to reduce the shock.

Ample space is needed below the track 7 for side projections of an aeroplane wing thereunder. The central column 12 must accordingly be of small dimensions but of great strength as it cannot be stayed and yet must be capable of resisting the bending moment due to the forces applied to the top of the mast through the arm 2. For a mast 100 feet high a steel tube 4' 6" or a little more in diameter built of thick steel plates, or of cast steel braced with tie rods, might be suitably strongly anchored to the ground. For a 150' mast it may be necessary to increase the diameter to 6' 0" or more.

A working platform 62 on which the various winches and mechanism is mounted may be provided above the track.

The mast above the track 7 may be guyed to the braced structure 61 supporting the said

track by suitable guys 63, 63 thus reducing the size and weight of the mast 1.

The mast 1 may be built up of steel plates or be of any suitable construction. If made of 5 steel plates the ropes 15, 22, etc., might be inside the mast.

At the top of the mast the arm 2 or revolving head 44 might be provided with a vane 64.

The ring or loop 3 although spread out wide 10 to receive an aeroplane will, directly an aeroplane has attached on, pull out into an elongated loop. To prevent the wire which forms the stress resisting portion of the loop from being bent to too sharp a curve, the part 47 of 15 the hook on the aeroplane and the surface of the horn 5 leading thereto may be widened out laterally and given easy curves.

The wire rope forming the loop must naturally be very flexible. If desired a flexible 20 wire rope may be anchored to the part 29 and after passing round the loop 3 and through an eye on the part 29 a suitable number of times, say 6 or 8 times, the further 25 end be also anchored to the said part 29. Various loops on the rope may be suitably lashed or bound together to make a single rope of great strength and flexibility.

It will be of course understood that the 30 invention is not restricted to the embodiment described and illustrated.

For example the details might be much modified, within the scope of the invention.

Instead of springs for controlling the paying out gear it might be possible to substitute 35 a system of weights or hydraulic or like cylinders, so that as the rope is paid out the tension should progressively increase.

The gear might be duplicated to suit the 40 size or weight of the various aeroplanes to be handled.

It has been suggested to use a crane with a vertical pole and a fixed horizontal arm thereon for the purpose of launching and landing aeroplanes, which crane was to be 45 mounted in a vertical bearing and capable of rotating with its fixed horizontal arm therein. To the end of the arm a sheave was fixed and a hoisting arrangement was mounted on the base of the pole. In launching, an 50 aeroplane was fixed to a rope which passed over the said sheave and was taken to the hoist. The aeroplane was raised clear of the ground by the operation of the hoist, and the aeroplane's engine started. The aeroplane 55 being thus suspended from the outer end of the horizontal arm caused the crane to rotate, and as the aeroplane and the crane gathered speed the rope was gradually paid out enabling the aeroplane to swing outwards and upwards. Upon the aeroplane having 60 accelerated both itself and the crane to obtain flying speed the rope was cast off from the crane and the aeroplane allowed to fly off trailing the long length of rope behind it. 65 In landing an aeroplane the aeroplane cir-

ced round with the rope trailing on the ground and it was suggested that the rope might be caught whilst so trailing, brought to the crane, and attached thereto and the aeroplane pulled in.

The present invention is however entirely different as it does not contemplate using a crane or any apparatus with a fixed horizontal arm. On the contrary it uses a landing mast with a rotatable arm thereon which can not only rotate or be rotated but can also have its outer end lowered. The principle underlying the present invention is completely different as the arm is used to whirl or to enable an aeroplane to whirl or be whirled about the mast upon the rising and falling end of the arm so that the aeroplane starts from the lowered hanging position and is gradually swung outwards and upwards whilst still controlled all the time by the arm until a suitable flying speed, elevation and circular path of suitable radius is attained. The aeroplane is then cast off and is completely independent of any rope. In landing an aeroplane, the same hooks on to the arm, which may be rotating around the mast at the time, and is gradually brought to rest as it whirls on a gradually falling spiral around the mast, being under the control of the arm all the time.

It has been proposed in aeroplane launching and landing gear to provide a tower with an arm capable of rotating around or being rotated around the top of the tower when in a horizontal position.

And it has been proposed to raise an aeroplane attached to a bight of cable hanging from the lower side of the said arm, and when the said arm is horizontal and the aeroplane in raised position hanging therefrom, to start the engine of the aeroplane or to start rotating the arm until sufficient speed is attained to launch the aeroplane. In this proposed device the arm was of stiff, rigid construction and was pivoted so that its outer end could be lowered to enable the aeroplane to attach thereto.

As said arm had necessarily to be of sufficient strength to lift the aeroplane hanging from its end and the arm acting as a cantilever had to be of considerable strength, stiffness and weight and had accordingly rather an undesirable inertia.

According to the present invention the arm, whilst capable of rotating or being rotated as in the proposed construction and being capable of swinging upwards, is very much lighter in that it is intended not to lift the arm as a cantilever but merely to swing it out and upwards as the aeroplane and arm rotate around the mast.

The arm accordingly acts mainly in tension and may be made very light and hence have little inertia. The arm also holds and directs the aeroplane all the time as it swings up

from the lowered to the launching position. Means moreover may be provided whereby the arm as it swings up pays out the aeroplane.

5 Having now particularly described and ascertained the nature of my said invention and in what manner the same is to be performed, I declare that what I claim is:—

1. Apparatus for despatching and landing aeroplanes, comprising a landing mast; a pivoted arm carried by said mast, and revolvable thereabout; an attachment device on the outer end of said arm for receiving an aeroplane; means balancing and controlling said arm in such manner that under the weight of a motionless aeroplane hanging from the end of the arm, the said arm will assume a downwardly inclined position, but which arm, as the aeroplane gathers speed around the mast, 15 revolves about and will assume a raised position gradually approaching the horizontal, with its end sweeping through a path having a continually increasing radius and means for releasing or attaching an aeroplane at 20 the desired position of the arm to the horizontal.

2. Apparatus for despatching and landing aeroplanes where the available space is limited, comprising a mast; a pivoted arm; an attachment device on said arm for carrying an aeroplane thereon and rotatable about said mast and swingable up and down in the plane of the mast; means for rotating said arm about said mast; means limiting the lowermost position of said arm; and means balancing and controlling said arm in such manner that when an aeroplane is attached thereto and the said aeroplane is motionless or moving around the mast at slow speed the 30 arm will hang with its outer end in a lowered position but is prevented from dropping below a limiting position in which the end of the arm and the aeroplane is held or constrained to travel on a circular path having a radius sufficient to prevent the aeroplane's wing from touching the mast, and when the aeroplane is moving around the mast at a higher speed the said arm will take up a more elevated position continually approaching the 40 horizontal with its end describing a circular curve or continually increasing radius as the centrifugal forces due to the speed of rotation of the aeroplane and the arm around the mast increases.

3. Apparatus for landing and despatching aeroplanes, comprising a mast; an arm adapted to rotate about the longitudinal axis of the mast pivotally attached adjacent the top of the mast and capable of assuming any position between a fully extended upper position in which the said arm may approach the horizontal, and a limiting lower position with the arm sharply inclined to the axis of the mast; means defining the limiting positions of said arm, the said arm when in said lower

limiting position making contact with a circular track surrounding the base of the mast, around which track the said lower end of the arm may slide or roll, and means at the outer end of the arm for the attachment or detachment of aeroplanes thereto or therefrom.

4. Apparatus according to claim 1, in which a resilient member controls the position of the pivoted arm.

5. Apparatus according to claim 1, in which at least one spring is used in combination with cables or the like, the tension or pull in said spring being such that it will, when allowed to act, cause the pivoted arm to rise to its raised, substantially horizontal position; and means for relieving or releasing the tension of said spring to enable the pivoted arm to drop to its lowered position.

6. Apparatus for despatching and landing aeroplanes comprising a landing mast; a pivoted arm carried by said mast and revolvable thereabout; an attachment device on the outer end of said arm for receiving an aeroplane; means balancing and controlling said arm in such manner that under the weight of a motionless aeroplane hanging from the end of the arm, the said arm will assume a downwardly inclined position, but which arm, as the aeroplane revolves about and gathers around the mast, will assume a raised position gradually approaching the horizontal, with its end swinging through a path having a continually increasing radius; means for releasing or attaching an aeroplane from or to the arm at the desired position of the arm to the horizontal; a crank device on said pivoted arm adjacent its pivotal point; and a spring to which the crank arm of said crank device is connected in such manner that as the end of the arm sinks the tension in the said spring is increased.

7. Apparatus according to claim 6 including means for adjusting the initial tension of the spring so that when the said arm sinks to its lower limiting position the tension in the spring may be adjusted to reach a selected ultimate value dependent on the anticipated weight of the aeroplane to be landed.

8. Apparatus according to claim 6 including means for slackening off at will the tension in said spring whereby if the aeroplane is not as heavy as is anticipated, the said arm will come to rest, when an aeroplane is being landed above the limiting lower position, and may thereafter be lowered gently to said lower position by slackening off the tension in the said spring.

9. Apparatus for despatching or landing aeroplanes, comprising a landing mast; a pivoted arm carried by said mast, and revolvable thereabout; an attachment device on the outer end of said arm for receiving an aeroplane; means balancing and controlling said arm in such manner that under the weight of

a motionless aeroplane hanging from the end of the arm, the said arm will assume a downwardly inclined position, but which arm, as the aeroplane revolves about and gathers speed around the mast, will assume a raised position gradually approaching the horizontal, with its end sweeping through a path having a continually increasing radius; means for releasing or attaching an aeroplane from or to the arm at the desired position of the arm to the horizontal; means supporting said pivoted arm; at least one spring in combination with said supporting means, the tension or pull in said spring being such that it will, when allowed to act, cause the pivoted arm to rise to its raised horizontal position; means for releasing or relieving the tension of said spring to enable the pivoted arm to drop to its lower position; and mechanism by means of which the tension on the said supporting means for the pivoted arm may be adjusted to cause said arm to assume, or to tend to assume, a desired position.

10. Apparatus for despatching and landing aeroplanes, comprising a landing mast; a pivoted arm carried by said mast, and revolvable thereabout, said arm being substantially rigid in the direction of the vertical plane passing through the momentary position of the arm and the axis of the said mast, but being relatively flexible in a direction substantially perpendicular to the said plane; an attachment device on the other end of said arm for receiving an aeroplane; means balancing and controlling said arm in such manner that under the weight of a motionless aeroplane hanging from the end of the arm, the said arm will assume a downwardly inclined position, but which arm, as the aeroplane revolves about and gathers speed around the mast, will assume a raised position gradually approaching the horizontal, with its end sweeping through a path having a continually increasing radius; and means for releasing or attaching an aeroplane from or to the arm at the desired position of the arm to the horizontal.

11. Apparatus for despatching and landing aeroplanes comprising a mast; a pivoted arm; a rotatable head on said mast for carrying said pivoted arm; an attachment device on said arm for carrying an aeroplane thereon, and being rotatable about said mast and also swingable up and down in the plane of the mast; means limiting the lowermost position of said arm; and means for rotating said arm comprising a cable, rotating mechanism for winding said cable at variable speeds and means for driving said rotating mechanism at any selected speed, the cable passing around the said rotatable head and thence to the drum of said rotating mechanism; the said mechanism being rotated at a selected speed.

12. Apparatus according to claim 11 including means for releasing the cable, where-

by the pivoted arm may rotate freely when an aeroplane is landing.

13. Apparatus according to claim 1 including a vane or the like fixed to the pivoted end of said pivoted arm, said vane being adapted, because of its angular position with respect to the arm, to cause the said arm to assume a desired position relative to the direction of whatever wind is blowing.

14. Apparatus according to claim 3 including a wheel mounted on suitable bearings at the outer end of said pivoted arm, the said wheel being adapted to cooperate with the said circular track in such manner that when the arm descends to its limiting lowest position, the wheel engages and is adapted to run about the said track.

15. Apparatus for landing and despatching aeroplanes comprising a mast; an arm adapted to rotate about the longitudinal axis of the mast, pivotally attached adjacent the top of the mast and capable of assuming any position between a fully extended upper position in which the said arm may approach the horizontal, and a limiting lower position with the arm sharply inclined to the axis of the mast; means defining the limiting positions of said arm; a circular track surrounding the mast adjacent the base thereof, the said arm when in its said lowering position making contact with said track and around which track the said lower end of the arm may slide or roll, and means at the outer end of the arm for the attachment or detachment of an aeroplane thereto or therefrom, the said mast being of smaller diameter below the circular track than above said track, whereby the wings of the aeroplane may enter below the track.

16. Apparatus for landing and despatching aeroplanes comprising a mast; an arm adapted to rotate about the longitudinal axis of the mast, pivotally attached adjacent the top of the mast and capable of assuming any position between a fully extended upper position in which the said arm may approach the horizontal, and a limiting lower position with the arm sharply inclined to the axis of the mast; means defining the limiting positions of said arm; a circular track surrounding the mast adjacent the base thereof, the said arm when in its said lowering position making contact with said track and around which track the said lower end of the arm may slide or roll; means at the outer end of the arm for the attachment or detachment of aeroplanes thereto or therefrom, the said mast being of smaller diameter below the circular track than above said track, whereby the wings of the aeroplane may enter below the track; a working platform on said mast above said circular track; arm-raising and lowering gear mounted on said platform; aeroplane-attachment-paying-out gear on said platform;

and means also mounted on said platform for operating said two gears.

17. Apparatus for despatching and landing aeroplanes, comprising a landing mast; a pivoted arm carried by said mast and revolvable thereabout; an attachment device for receiving an aeroplane on the outer end of said arm; means on said arm for releasing or attaching an aeroplane thereto at a desired position of said arm to the horizontal; and cables connected to the attachment device in such manner that the said attachment device may, when desired, be extended to enable the radius of the curve on which the aeroplane is caused to move about the mast to be extended beyond that permitted by the length of the pivoted arm.

18. Apparatus according to claim 17 in which the attachment device comprises a spring-extended loop of cable which is normally opened wide and capable of being readily engaged by cooperating means on the aeroplane, and which under the action of the spring, when the weight of the aeroplane comes thereon, lengthens into a narrow loop capable of carrying the weight of the aeroplane and of resisting the centrifugal and similar stresses.

19. In combination, apparatus for despatching and landing aeroplanes comprising a landing mast; a pivoted arm carried by said mast and revolvable thereabout; an attachment device on the outer end of said arm for receiving an aeroplane; and engaging gear on the aeroplane for cooperation with said attachment device, said engaging gear comprising a projecting horn; means for forwardly projecting said horn when the aeroplane is about to engage the attachment device; the said horn having a depression or indent in the hook or curve thereof adapted to receive and engage the said attachment device; and a grip or catch for preventing the aeroplane, once hooked, from accidentally disengaging with the said attachment device.

20. In combination, apparatus for despatching and landing aeroplanes comprising a landing mast; a pivoted arm carried by said mast and revolvable thereabout; an attachment device on the outer end of said arm for receiving an aeroplane; and engaging gear on the aeroplane to be landed or despatched, said engaging gear comprising a horn and hook; spring means for cushioning the shock of landing and also adapted to extend in launching under the weight of the aeroplane and the action of the centrifugal force; and an indicator for showing the stress on the said springs, and thereby indicating when such stress in launching has been sufficiently reduced to enable the aeroplane to cast off from the attachment device with safety.

In testimony whereof I hereto affix my signature this fourteenth day of July, 1928.
